US0D1047076S

(12) **United States Design Patent** (10) **Patent No.:** **US D1,047,076 S**
(45) **Date of Patent:** **** Oct. 15, 2024**

(54) **HYDROGEN WATER GENERATOR**

(71) Applicant: **Hanqin Li**, Anhui (CN)

(72) Inventor: **Hanqin Li**, Anhui (CN)

(**) Term: **15 Years**

(21) Appl. No.: **29/951,282**

(22) Filed: **Jul. 9, 2024**

(51) LOC (14) Cl. **23-01**

(52) U.S. Cl.

USPC **D23/209**

Primary Examiner — Keith J Wilson

(57) **CLAIM**

The ornamental design for a hydrogen water generator, as shown and described.

DESCRIPTION

FIG. 1 is a perspective view of a hydrogen water generator showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the hydrogen water generator, which form no part of the claimed design.

1 Claim, 8 Drawing Sheets
